F. WOLFF

GAS MIXER

Filed Dec. 21, 1923

Inventor:
Friedrich Wolff
By
B. Singer, Atty.

UNITED STATES PATENT OFFICE.

FRIEDRICH WOLFF, OF BERLIN, GERMANY, ASSIGNOR TO SELAS AKTIENGESELLSCHAFT, OF BERLIN, GERMANY.

GAS MIXER.

Application filed December 21, 1923. Serial No. 682,078.

To all whom it may concern:

Be it known that I, FRIEDRICH WOLFF, a citizen of the German Republic, and a resident of Berlin, Germany, have invented 5 certain new and useful Improvements in Gas Mixers, of which the following is a specification.

In gas burners or jets as they are used for industrial purposes the admission of the 10 gases to be mixed, combustible or illuminating gas, air and sometimes oxygen into a common mixing device for the supply of a number of burners, or into a mixing chamber for the supply of one or more burners, 15 takes place either under even pressure or under various pressures in such a manner, that the air is admitted under the greater pressure and is used to force the gas into the mixing chamber by the employment of 20 nozzles and injectors.

It is to these types of gas mixing arrangements that my invention bears special reference, and its main object is to eliminate the 25 possibility of air entering the gas conduit when the pressure in the same happens to fall below a certain amount, or of gas entering the air conduit when the pressure in the latter happens to fall off. In both these cases there exists a great risk of danger as 30 explosive mixtures may form in the conduits, in the gas meter or in the compressor, which may easily lead to explosions when the flame should happen to fire back after the burner has been ignited.

35 Since it is very difficult to arrange ordinary stop valves for the elimination of these risks, because of the difference in the pressures between gas and air being normally very small, the said object of the invention is effectively realized by the provision, within 40 the conduits leading to the mixing chamber, of individually controlled special stop valves, which will easily respond to even slight variations in the pressure.

45 Another object of the invention is the provision of means, in connection with the said special stop valves, for enabling a sufficient force being exercised upon the valve proper on the pressure in the conduits, or conduit, falling below a predetermined minimum.

Another object of the invention consists 50 in the combination of the said special stop valves with such regulating valves for the gas or the air, as they are sometimes used

in this kind of gas mixing arrangements, the arrangement then being such that the actuating organ of the regulating valve may simultaneously be used to serve as the actuating member of the said special stop valves 60 also.

Further objects of the invention are the generally improved and simplified arrangement and combination of parts in gas mixing devices of the said type as hereinafter 65 more fully described with reference to the accompanying drawings, in which several modifications of the invention are illustrated by way of example.

In these drawings,

70 Fig. 1 is a largely diagrammatic view in part-sectional side elevation of a complete gas mixing arrangement according to the invention, including the burner installation,

Fig. 2 illustrates one form of the special 75 stop valves in vertical section,

Fig. 3 shows a modified form of the said special stop valve in vertical section.

Fig. 4 illustrates the combination of two 80 special stop valves with a mixing device for gas and air in part-sectional side elevation.

Referring in particular to Fig. 1, the mixing arrangement consists of the gas conduit 1, gas meter 2 which is in connection 85 therewith, air conduit 3 and a compressor 4, the mixing device proper for gas and air consisting of a nozzle and injector 5 at the connection between gas conduit 1 and air conduit 3, and of the burner 6 for the heating, for example, of a tempering forge 6'. In the gas conduit 1 and the air conduit 3 the stop valves 7 and 7' respectively are arranged. Each of the said stop valves, of which one is shown in Fig. 2 on an enlarged scale, includes a casing 8 having inlet and outlet connections 9 and 10 respectively and also includes a regulating valve, a lever and a diaphragm as hereinafter 90 described. Referring particularly to Figure 2, 95 11 is a valve seat adapted to be closed by a regulating valve body 12 which is under the action of a diaphragm 15 by the intermediary of a two-arm lever 14 rocking about its fulcrum 13. The action of the diaphragm may, if desired, be increased by the application of a weight 16. Under the influence of normal working pressure this diaphragm, which is connected to the lever 14 by means of a link 14', holds the valve 11,

100 105 110

12 in open position, whereas on the pressure on the admission side decreasing below a certain minimum, the said diaphragm and the weight 16, if such is provided, come into operation and, pressing the link 14' downwardly, cause the closing of the valve 11, 12. It is evident, that the diameter of the diaphragm should be sufficiently large to ensure such closing taking place even at comparatively narrowly limited differences in the gas or air pressure.

The modification of the safety device for the protection against back firing as shown in Fig. 3 differs from the aforesaid in that the valve 12^a with its connected diaphragm is directly combined with a regulating valve for the gas or air pressure. As in the former example, 8^a denotes the valve casing, 9^a the entrance and 10^a the exit for the gas or air respectively, and 11^a is the valve seat adapted to be closed by the valve 12^a which, by means of lever 14^a, fulcrumed at 13^a, is under the influence of the controlling diaphragm 15^a. In connection with the said diaphragm, as by means of a valve rod 17^a, is a valve cone 19 adapted to control the valve passage 18. From the drawing (Fig. 3) it will be evident, that the adjustment of the regulating valve cone 19 depends on the extent or degree of curvature of the diaphragm 15^a which, in turn, depends on the pressure of the gas or air admitted through the conduit. According to the amount of this pressure the effective valve opening 18 will be more or less throttled. The valve 12^a of the special stop valve (Fig. 3), on the other hand, is so disposed with regard to its seat 11^a that the mere regulation lifts of the valve 19 will always leave sufficient clearness between the valve 12^a and its seat to prevent throttling influence on the gas current. Should the regulating valve 19 with falling pressure open beyond a predetermined amount, so that there would be a risk of air entering from the air conduit into the casing 8^a and the gas conduit 1, the valve 12^a would close down on its seat and thus prevent the danger of the formation of an explosive mixture within the gas conduit.

In the arrangement according to Fig. 4 the two stop valves 7 and 7' for the passage of air and gas in combination with regulating valves such as shown in Fig. 3 are illustrated as being joined to a mixing device 20, into which they deliver gas and air re-

spectively. The said mixing device consists of a chamber 20' comprising a slide valve 22 which is actuated by the vibrations of a diaphragm 21, and by means of which the calibrated admission openings 23 and 24 are controlled so that the mixing ratio of gas to air always remains constant. The figure shows the slide valve 22 of the mixing device in its working position. As soon as gas and air enter under pressure this slide valve moves to cover the ports 23 and 24 until the pressure in the conduit 25 for the mixture has attained the amount which is determined by the weight of the slide valve 22 and the diameter of the diaphragm. In the ordinary position, however, the entrance ports for gas and air are completely open.

What I claim is:

1. In a gas mixing arrangement, a gas conduit and an air conduit introducing gas and air under pressure, a mixing device to which said conduits lead, a stop valve in each of the said conduits, each stop valve including a casing forming part of one of the said conduits and also including a diaphragm in said casing and acted upon by the pressure in the conduit on one side, and by atmospheric pressure on the other side, a regulating valve, a two-arm lever between the regulating valve and the associated diaphragm, and links to connect one end of the said two-arm lever to the regulating valve and the other to the diaphragm so as to close the regulating valve on the pressure in one of the conduits falling below a certain amount.

2. In a gas mixing arrangement having gas and air conduits, the combination within each of the said conduits of a stop valve, a pressure regulating valve, a valve, a common pressure responsive element, all arranged in a casing, with a mixing chamber in connection with each of the said stop valves, a pressure responsive element in the said mixing chamber, and a slidable member in the said chamber actuated by the said pressure responsive element so as to open the admission ports for gas and air when the device is at rest, and to partially close same when at work until balance is established between the working pressure on one side of the said element and the atmospheric pressure on the other side.

In witness whereof I affix my signature.

FRIEDRICH WOLFF.
